UNITED STATES PATENT OFFICE.

ALEXANDER A. CLEMONS, OF MARBLEHEAD, OHIO.

CAR RIGHTER.

Application filed December 20, 1923. Serial No. 681,735.

To all whom it may concern:

Be it known that I, ALEXANDER A. CLEMONS, a citizen of the United States, residing at Marblehead, in the county of Ottawa and 5 State of Ohio, have invented certain new and useful Improvements in Car Righters, of which the following is a specification.

This invention relates to improvements in car righting apparatus, and more particularly to an apparatus for returning a tilted car body to horizontal position while the car is moving along supporting rails. The apparatus is especially suitable for righting dump car bodies which tilt sidewise.

15 The primary object of the invention is to provide a car righting apparatus including an inclined ramp or cam arranged alongside the railway rails and designed to abut against a tilted car body as the car moves 20 along the railway rails, and to lift the car body back to horizontal position. The car body may be then latched in the ordinary manner, so as to maintain its horizontal position.

25 A further object of the invention is to provide a car righter of the above character in which the ramp or cam is movable toward and away from the railway rails, so that the ramp may be moved out of the 30 way, when it is not in use.

A further object is to provide a ramp or cam with shock absorbing means so as to permit the ramp to give or spring to prevent the breaking of its operating mechanism.

35 With the foregoing objects outlined and with other objects in view which will appear as the description proceeds, the invention consists of the novel features hereinafter described in detail, illustrated in the accompanying drawings and more particularly pointed out in the appended claims.

40 Referring to the drawings:

Fig. 1 is a side view of the improved car righting apparatus shown in use with a dump car, the latter being diagrammatically 45 illustrated.

Fig. 2 is a top plan view of the main portion of the car righter.

Fig. 3 is an enlarged side view of the apparatus.

50 Fig. 4 is a vertical sectional view taken on line 4—4 of Fig. 2.

In the drawings, 1 designates railway rails on which travel the trucks 2 of cars 55 having tilting bodies 3.

My improved apparatus preferably in-

cludes a beam 4 extending beneath the rails and provided at one side of the rails with two channel-shaped irons 5, which are secured to the beam by means of the bolts 6. 60 Angle irons 7 are slidably mounted in the channel irons and to permit adjustment each angle iron has a slot 8 through which pass bolts 9 connected to the channel irons.

The angle irons carry a bolt shaft 10 on which is pivotally mounted an inverted U-shaped standard 11, a pipe 12 being arranged on the bolt 10 between the legs of the standard for spacing and reinforcement purposes. A second bolt 13 reinforces the 70 standard 11 and is provided with a spacing pipe or sleeve 14. An upper or third bolt 15 is also carried by the standard and this bolt is provided with spaced pipes or sleeves 16.

The bolt 15 passes through an elongated slot 17 in a link 18. The bolt 15 also extends through an eye 19 formed at one end of a shank 20 which is slidably mounted in a lug 21 extending outwardly from one side of the link 18. A washer 22 is mounted on the link 18 and abuts against the lug 21, and a spring 23 surrounds the link 18 and shank 20, and bears at one end against the washer 22 and at the other end against the bolt 15. 80 Owing to this construction the standard 11 may rock in counter-clockwise direction (in Fig. 3) without moving the link 18.

A cam or ramp 24 is supported by the upper end of the standard 11 and this ramp preferably consists of two parallel sections of railroad rails bolted at 25 to the head of the standard 11 and braced by means of braces 26. It may be seen from Fig. 4 that the ramp 24 is inclined relatively to the horizontal, and it may be seen from Fig. 2 that the ramp is also inclined relatively to the railroad rails 1. Consequently when the ramp is in position to engage the outer edge of a tilted car body 3, while the car is moving in the direction of the arrow A in Fig. 2, the car will first strike the end 24^a of the ramp and will then ride along the ramp and be gradually raised into horizontal position.

100 For the purpose of swinging the standard 11 and ramp 24 toward and away from the rails 1, the link 18 is pivotally connected at 27 to a lever 28. This lever is pivotally connected at 29 to a bracket 30 secured to the 105 beam 4. The lower end of the lever 28 is pivotally connected at 31 to an elongated

link 32 which extends beneath the rails 1 and is provided on the opposite side of the track with a pin 33, which pivotally connects the same to an operating lever 34 having a hand actuated latch 35 cooperating with a tooth quadrant 36.

From the foregoing description it will be understood that the operator, say at the left hand side of the rails 1, may actuate the lever 34 and throw the standard 11 and ramp 24 into position to engage the tilted car bodies, or out of position, so that the ramp will not obstruct other traffic. It will also be recognized that the spring 23 will permit movement of the ramp 24 toward the lever 28 relatively to the link 18 so that shocks in one direction will be absorbed without breaking the mechanism.

In view of the above description, it is believed that the construction, operation and advantages of the invention may be readily understood by those skilled in the art and it is apparent that changes may be made in the details disclosed without departing from the spirit of the invention as expressed in the claims.

What I claim and desire to secure by Letters Patent is:

1. The combination with a railway track and a standard dump-car movable along the same, of a car righter arranged alongside of the railway track and including a standard, an inclined ramp supported by said standard and extending upwardly from a point above the level of the track to an elevation only slightly above the car wheels for lifting the bodies of dump-cars moving along the track, and means for moving and inclining the standard and ramp toward the track.

2. A car righter including a standard adapted to be arranged alongside of a railway track and consisting of an inverted U-shaped member and bolts connecting the legs of the inverted U-shaped member, an inclined ramp supported by said standard and adapted to raise the bodies of dump-cars moving along the track, and means for moving said standard and ramp toward and away from the track.

3. A car righter including supports, angle irons connected to and slidably mounted on said supports, a standard connected to said angle irons and adapted to be arranged alongside of the railway track, an inclined ramp supported by said standard and adapted to raise the bodies of dump-cars moving along the track, and means for moving said standard and ramp toward and away from said track.

4. A car righter including a standard mounted for pivotal movement and adapted

to be arranged alongside of a railway track, an inclined ramp supported by said standard and adapted to raise the bodies of dump-cars moving along the track, and means for moving said standard and ramp toward and away from the track, said means including a rocking lever, a link connecting the lever and standard, and means for actuating said lever.

5. A car righter including a standard adapted to be arranged alongside a railway track, an inclined ramp supported by said standard and adapted to raise the bodies of dump-cars moving along the track, and means for moving said standard and ramp toward and away from the track, said means including a link connected to the standard, a lever connected to the link, a second elongated link connected to the lever and adapted to extend beneath the car track, and an operating lever for actuating the elongated link.

6. A car righter including a standard, a ramp supported by the standard and inclined relatively to the horizontal, and resilient means for holding the standard and ramp in one position.

7. The combination with a railway track, of a standard arranged at one side of the track and a control member arranged at the opposite side of the track, a ramp supported by the standard and inclined relatively to the horizontal, and means connecting the control member to the standard to permit the standard to be moved toward and away from the track when said control member is actuated.

8. In a car righter, the combination with a movably mounted standard, of a ramp supported by the standard and inclined relatively to the horizontal, a link connected to the standard by a slot and pin connection, and a spring for normally holding the pin at one end of said slot.

9. A car righter including supporting bars adapted to be arranged at one side of a railway track, angle irons connected to and slidably along said bars, a standard pivotally connected to said angle irons, a ramp supported by the standard and inclined relatively to the horizontal, and means for rocking said standard to permit movement of the ramp toward and away from the railway track.

10. A car righter as claimed in claim 9 in which the means for rocking said standard includes a resilient element to permit movement of the standard relatively to the rocking means.

In testimony whereof I hereunto affix my signature.

ALEXANDER A. CLEMONS.
